Patented Dec. 14, 1920.

INVENTOR
LEONARD PORTEOUS
BY
ATTORNEY
E.H. Bond

UNITED STATES PATENT OFFICE.

LEONARD PORTEOUS, OF SHARON, PENNSYLVANIA.

BUMPER FOR BOATS.

1,361,902.

Specification of Letters Patent. Patented Dec. 14, 1920.

Application filed March 1, 1920. Serial No. 362,394.

To all whom it may concern:

Be it known that I, LEONARD PORTEOUS, a citizen of the United States of America, residing at Sharon, in the county of Mercer, 5 and State of Pennsylvania, have invented certain new and useful Improvements in Bumpers for Boats, of which the following is a specification.

This invention relates to bumpers for 10 boats which consists of an air chamber having suitable lugs and suitable means for engaging said lugs to the side of a boat.

Figure 1 designates a boat with my improved bumper attached thereto,

15 Fig. 2 shows a side elevation of the bumper, the side of the boat being in section,

Fig. 3 shows a modified form of the bumper used for the end of the boat,

20 Fig. 4 shows a pear-shaped bumper of similar construction,

Fig. 5 is a sectional view of the modified form of my invention having looped lug attaching means, and

25 Fig. 6 is an enlarged view of the attaching means.

Fig. 7 is a view of a belt which may be applied to fasten the bumper about the body of a person.

30 Referring to the drawings like numerals designate like parts in the various drawings.

7 indicates a boat of any design on which bumpers are usually used to keep the boat from rubbing against the side walls of locks 35 or other places where the boat will be passing through and where otherwise the boat would become damaged if allowed to rub thereagainst.

In my improved bumper I provide an air 40 chamber 8, which may be made of any suitable material, having an opening at one end and the valve 9 attached thereto, which valve is protected by the usual cap 10. The air chamber 8 is inflated through the valve 9.

45 Suitably attached to the air chamber 8 I provide lugs 11 which may be of any desirable shape adaptable for the purpose of attaching the air chamber to the side of a boat. These lugs are preferably provided

50 with the receiving portion of a glove fastening member 12 while on the side of the boat at predetermined positions are the stud portions 14, which are adapted to be received into the receiving portions 12. The stud 55 portions 14 are provided with openings 15 in which suitable screws or nails can be in-

serted for attaching the stud portions to the side of a boat. By this means I provide a quick detachable arrangement whereby the bumpers can be readily changed from one 60 side of the boat to another as requirements demand.

I do not wish to limit myself to the particular design of air chamber 8 as shown in Fig. 2, as it might be formed in the shape as 65 shown in Fig. 3 as at 8^a which particular shape is found most adaptable for the front of a boat.

I do not wish to limit myself to the particular fastening means as illustrated in Fig. 70 6, as in some cases the bumper is attached to the end of a rope so that it can be thrown over the side of a boat in navigation purposes when coming through locks and is drawn up as soon as the boat passes through 75 the locks. Such a bumper is illustrated in Figs. 4 and 5. The lug 11^a in this instance is provided with a looped end so that a rope may pass therethrough.

I wish further to explain that with such 80 bumpers being used on boats that they practically become life-saving devices in case of a wreck, which is of great assistance at such a time. In Fig. 7 I illustrate a belt which belt is provided with studs 14^a, which studs 85 are similar to the studs 14 and are positioned apart at a predetermined distance so that in the case of a wreck the air chamber 8 can be detached from the side of the boat and the receiving portions 12 snapped over 90 the studs 14^a. The belt can then be attached around the body of a person and thus used as a life preserver. In a similar manner the belt can be passed through the looped ends of the lugs 11^a as illustrated in Fig. 5 95 and the belt passed around a person's body to act as a life preserver.

From the foregoing it is thought that the construction of my invention will be clearly understood, and, therefore, a more extended 100 explanation has been omitted.

What I claim as new and desire to secure by Letters Patent, is,—

1. A bumper for a boat consisting of an air tight chamber having an opening into 105 the same, a valve positioned in said opening whereby air may be pumped into said air chamber, lugs formed on the side of said air chamber whereby the said air chamber may be positioned on a boat to keep the latter 110 from rubbing while going through locks or other similar places.

2. A bumper for a boat consisting of an air tight chamber, an opening into said chamber, a valve adapted to receive and hold air in said chamber, a cap covering said 5 valve, lugs attached to the side of said chamber, a receiving member of a glove fastening device positioned in said lugs, stud portion of a glove fastening device suitably positioned on a boat and adapted to receive said 10 receiving member so as to hold said air chamber in a detachable manner to said boat.

3. A bumper for a boat consisting of an

air tight chamber, an opening into said chamber, a valve adapted to receive and hold 15 air in said chamber, lugs formed from said chamber, a means whereby said lugs can be detachably fastened to a boat, said bumper being adaptable as a life preserver.

In testimony whereof I affix my signature 20 in the presence of two witnesses.

LEONARD PORTEOUS.
